DESIGN FOR A PORTABLE SLEEPING STRUCTURE FOR MOUNTING ON TOP OF AN AUTOMOBILE

Norris S. Smith, Los Angeles, Calif.

Application August 30, 1946, Serial No. 132,956

Term of patent 14 years

(Cl. D14—27)

To all whom it may concern:

Be it known that I, Norris S. Smith, a citizen of the United States, residing at Los Angeles, in the county of Los Angeles and State of California, have invented a new, original, and ornamental Design for a Portable Sleeping Structure for Mounting on Top of an Automobile, of which the following is a specification, reference being had to the accompanying drawing, forming part thereof.

Figure 1 is a view in perspective of a portable sleeping structure for mounting on top of an automobile, showing my new design, the opposite side being the same as illustrated; and

Figure 2 is an elevational view of the end opposite to the end shown in Figure 1.

I claim:

The ornamental design for a portable sleeping structure for mounting on top of an automobile, as shown and described.

NORRIS S. SMITH.
